COIN CONTROL MECHANISM FOR VENDING MACHINES

Filed April 17, 1929

INVENTOR:
S. J. SWANSON.

BY *Arthur C. Ecker*
ATTORNEY.

UNITED STATES PATENT OFFICE

SWAN J. SWANSON, OF ST. LOUIS, MISSOURI, ASSIGNOR OF ONE-HALF TO UGO DALPINI,
OF ST. LOUIS COUNTY, MISSOURI

COIN-CONTROL MECHANISM FOR VENDING MACHINES

Application filed April 17, 1929. Serial No. 355,810.

The object of my invention is to make a coin control mechanism for vending machines. A further object is to make a coin control mechanism for a plurality of different sized coins. In the vending of articles that sell for amounts that require more than one coin my device finds a particular application. If the article to be vended sells, for instance, for forty (\$.40) cents, it will require the insertion of a quarter of a dollar, a nickel and a dime. In my device these three coins may be inserted and by the manual turning of a single handle, the coins passed through the control mechanism into the coin container, and at the same time, the commodity actuating device cause to function in order to remove the commodity to be vended from its container to the vendee. My present invention is limited to the coin control mechanism together with the coin container and a single arm rotatively mounted, which arm represents the contact between my device and the commodity distributing system, which forms no part of my present invention. My device is made of few and simple parts that lend themselves readily to multiple production. It may be easily and cheaply made, assembled and repaired. It is so constructed that it will not function except when the proper sized coins, and the proper number of such coins are inserted in the control mechanism. The device may be made to accommodate as many different coins as desired. The illustration in this application shows the device designed for the use of quarters, nickels and dimes. Of course, the device may be also used where it is only desirous of actuating the control mechanism by a single coin.

With these and other objects in view my invention has relation to certain novel features of construction and arrangement of parts as will be hereinafter more fully described, pointed out in the claim and illustrated in the drawing, in which

Fig. 1 is a front elevation of my device.
Fig. 2 is a side elevation of my device.
Fig. 3 is a sectional plan view of Fig. 2.
Fig. 4 is a sectional elevation of Fig. 3 showing a coin as originally inserted in the control mechanism.

Fig. 5 is a sectional elevation similar to Fig. 4, showing the coin immediately prior to its being dropped into the coin receptacle.

Numeral 6 designates the coin receptacle showing the coins 7 deposited therein. Numeral 8 designates the front plate of my device. The coin receptacle 6 is attached to the front plate 8. Numeral 9 designates the dime spout, numeral 10 the nickel spout and numeral 11 the quarter spout. These spouts are of such size as to accommodate the coins indicated and lead at their inner ends to coin slots to be subsequently described. Numeral 12 designates the coin control mechanism generally. My device is so constructed that if a coin smaller than the size indicated on a coin spout, is inserted in a coin spout, the coin will pass directly through the coin control mechanism 12 into the coin receptacle 6 without having any action on the coin control mechanism; that is, if a dime or nickel is inserted in the quarter slot or a dime is inserted in the nickel slot the coin will pass through the control mechanism into the coin receptacle without actuating the coin register and be lost to the operator. The device furthermore will not function if designed for forty (\$.40) cents; that is, having a quarter, nickel and dime slot, unless all three coins are inserted.

Numeral 13 designates a rectangular plate secured to the front plate 8 by means of the screws 14. In the center of the rectangular plate 13 is formed a hole 15. Numeral 16 designates a cylindrical shell, which is secured to the back of the rectangular plate 13, the shell 16 passing through a hole in the front plate 8. In the upper lateral face of the shell 16 are cut parallel arcuated slots, 17, 18 and 19. In the bottom lateral face of the shell 16, diametrically opposite to the slots 17, 18 and 19, are cut slots 20, 21 and 22, the slots opposite each other are the same size. The slots 17 and 20 are large enough to admit the largest coin in the illustration, a quarter; the slots 18 and 21 are large enough to admit the second largest coin, namely a nickel and the slots 19 and 22 are large enough to admit the smallest coin, only, namely a dime. It will be seen that when

the shell 16 is in the position shown in the drawing that if a quarter is inserted in the slot 17, it will fall through the shell 16 and out of the slot 20 into the coin receptacle 6; that if a nickel is inserted in the slot 18, it will fall through the shell 16 and out of the slot 21 into the coin receptacle 6; that if a dime is inserted in the slot 19, it will fall through the shell 16 and out of the slot 22, into the coin receptacle 6. Between the slots 17 and 18 is formed an arcuated slot 23; between slots 18 and 19 is formed an arcuated slot 24; between the slot 19 and the free face of the shell 16 is formed an arcuated slot 25. These slots 23, 24 and 25 are larger than the slots, 17, 18 and 19 and are of the same length and are used for purposes to be subsequently described. The inside surface of the shell 16 is cut away over the slots 20, 21 and 22, as shown at 26, forming the shoulder 27 at the right edge of the slots 20, 21 and 22. The inside face of the shell 16 is likewise cut away diametrically opposite to the cut away portion at 26, as shown at 28 beneath the slots 17, 23, 18, 24, 19 and 25 in an arcuated manner. Numeral 29 designates a cylindrical cup closed at one end by the wall 30. Numeral 31 designates a shaft centrally positioned on the wall 30. Numeral 32 designates an end closure secured in the open end of the cylindrical cup 29, by means of the screws 33. Numeral 34 designates a shaft centrally secured in the end closure 32; numeral 35 designates an arm secured to the free end of the shaft 34. Numeral 36 designates a projection formed on the free end of the arm 35.

The shaft 31 is of such size as to permit its insertion in the hole 15. The cylindrical cup 29 is of such size as to permit its insertion in the shell 16 by sliding engagement. When the cylindrical cup 29 is positioned in the shell 16, so that the shaft 31 projects through the hole 15, the cylinder 37 is secured to the end of the shaft 31 by frictional sliding engagement and by means of a pin 38, which passes through the cylinder 37 and the shaft 31. On the cylinder 37 is secured near its inner end, the pointer 39. Numeral 40 designates a handle, which is secured to the cylinder 37 by passage therethrough.

On the rectangular plate 13 at the upper vertical position of the pointer 39 is indicated the start for the rotation of the pointer 39.

By the structure thus far described, it will be observed that when the handle 40 is rotated that the cylindrical cup 29 will be likewise rotated in the shell 16, and that the arm 35 together with its projection 36 will be rotated. In the lateral surface of the cylindrical cup 29 are cut arcuated slots 41, 42 and 43. There are six of such slots, the one set of three being diametrically opposite to the other set of three. The slots are of the same length and

are of sufficient size to permit the passage of the largest coin that is used in the coin control mechanism 12 from one side of the cylindrical cup 29, through to the other side, through diametrically opposite slots. These slots are so positioned that when the cylindrical cup 29 is assembled as indicated in the drawings, the slot 43 will be in registration with the slots 17 and 20 of the shell 16; the slots 42 will be in registration with the slots 18 and 21 of the shell 16, and the slots 41 will be in registration with the slots 19 and 22 of the shell 16.

It will be seen that when this registration of slots is effected that coins inserted in the slots 17, 18 and 19 will pass through the shell 16 and the cylindrical cup 29 and be deposited in the coin receptacle 6.

The device as thus far described would simply permit the insertion of coins and the passage through the coin control mechanism into the coin receptacle 6 and permit the complete rotation of the pointer 39 as well as the arm 35 independent of whether or not coins had been inserted in the coin control mechanism. The object of my device is to be able to selectively rotate the arm 35 by means of rotating the handle 40, but only when the proper coins have been inserted in the coin control mechanism. The arm 35 together with its projection 36 is the part of my device that is used to actuate the merchandise delivery portion of the vending machine. It will be seen, therefore, that by the single manipulation of the handle 40, after the proper coins have been inserted in the coin register will cause the deposit of the coins in the coin receptacle 6, and also actuate the merchandise delivery mechanism. The handle 40 may be rotated in either direction through the small arc of a circle without the insertion of any coins, but this corresponding rotation of the arm 35 is not sufficient to actuate the commodity distributing mechanism. In order to permit the rotation of the handle 40 through a sufficient arc to rotate the arm 35 sufficiently to actuate the commodity distributing mechanism, it becomes necessary to insert the proper coins in the coin control mechanism. The means of accomplishing this result are the following:

In the lateral surface of the cylindrical cup 29 between the slots 41, 42 and 43 are formed the holes 44, 45 and 46. In the cylindrical cup 29 are positioned the coin guides 47. One of the purposes of these guides is to guide the coins in their travel through the cylindrical cup 29. As many coin guides 47 must be supplied as there are slots 17, 18 and 19. In other words, in the illustration there must be one such coin guide for the dime, one for the nickel and one for the quarter. The coin guides 47 are cylindrical disks of such a diameter as to fit in sliding engagement in the cylindrical cup 29. The total widths of the

coin guides 47 is such that when in position they will occupy all of the space in the cylindrical cup between the wall 30 and the end closure 32. There will be no space remaining between the coin guides 47 themselves and the wall 30 and the end closure 32. Centrally positioned in the coin guides 47 is formed the key hole shaped perforation 48 in the position best shown in Figs. 4 and 5. In the lateral surface of the coin guide 47 immediately above and below the key hole shaped perforation 48 are formed the holes 49 and 50. Numeral 51 designates a rod that is in sliding engagement in the holes 49 and 50. Numeral 52 designates a slide that is secured to the rod 51 by threaded engagement by means of a projection that extends in the key hole shaped perforation 48. Numeral 53 designates a coiled spring positioned in the hole 49 below the rod 51. Numeral 54 designates a plug in threaded engagement in the outer end of the hole 49. The rod 51 is of such length that in its normal position it projects slightly beyond the edge of the coin guide 47. It is held in this normal position by means of the coiled spring 53. The slide 52 together with the rod 51 can only be moved diametrically inwardly by compressing the coiled spring 53. Numerals 55 and 56 indicate guides that are secured to the surface of the coin guides 47 for the purpose of guiding the slide 52 diametrically and preventing a lateral movement. In assembling the coin guides 47 in the cylindrical cup 29, the rod 51 is depressed until its outer end is flush with the peripheral surface of the coin guide 47 and moved inwardly until the outer edges of the guides 55 and 56 come in contact with the inner face of the wall 30. The coin guide 47 is then turned until the end of the rod 51 protrudes through the hole 46. The outer edges of the guides 55 and 56 of this coin guide 47 will then come in contact with the inner face of the wall 30. On each of the slides 52 are formed two right angle projections 57 and 58 which are in sliding contact with the guides 55 and 56. The space between the inner ends of the right angle projections 57 and 58 is such that the coin that is intended to be inserted therein will be supported and prevented from passing through it, but of such size that the next smaller coin that is to be used in the device will pass through it. That is, in the illustration, the coin guide that is designed for the quarter will prevent the quarter from passing through, but will permit the nickel and dime to pass through; the guide that is designed for the nickel will prevent the nickel from passing through, but will allow the dime to pass through. This is done to prevent the operator from inserting a coin smaller than is intended and having the control mechanism function. If a nickel is inserted in the quarter slot, it will simply fall through to

the coin receptacle without actuating the device and the coin will be lost to the operator. After one coin guide has been inserted, for instance, the quarter guide in the illustration, the next coin guide for instance the nickel guide is similarly inserted; the outer face of the first coin guide acts as an outer wall to the subsequent coin guide and the outer wall surface of the second coin guide, acts as a wall for the next succeeding coin guide, etc.

When the coin guides have been assembled and the cylindrical cup 29 assembled in the shell 16, as indicated, the device is ready for operation. It will be observed immediately that the rotation of the handle 40 is limited, in both directions to the small arc of a circle when no coins are inserted. This limitation is caused by the protruding ends of the rods 51, which come in contact with the edges of the slots 23, 24 and 25.

In order to operate the control mechanism with coins, assume that the pointer 39 is in its vertical or starting position and that the handle 40 is in the horizontal position as shown in Fig. 1, insert a quarter in the quarter slot. It will now be observed that when the handle 40 is turned in either direction, that the coin will come in contact with the edge of the slot 17, and that when the turning is continued the coin will be forced radially inwardly compressing the slide 52 against the compression of the coiled spring 53, and that this will depress radially inwardly the protruding end of the rod 51 in the hole 46, and that now the continued rotation is prevented by the protruding ends of the rod 51 in the holes 44 and 45. In other words, the operation of the control mechanism is prevented by the mere insertion of the quarter. Assuming now that the pointer 39 is in its original position and a nickel inserted in the nickel slot, the same rotation will be permitted as in the initial instance. In this case the nickel coming in contact with the edge of the slot 18 depresses the slide 52 and the protruding end of the rod 51 in the hole 45. The continued rotation is now prevented by the protruding end of the rod 51 in the hole 44.

Now assuming that the pointer 39 is in its original position insert the dime in the dime slot and continue the rotation in either direction as before. It will now be seen that the rotation is not limited because the last obstacle to the rotation has been removed, namely the protruding end of the rod 51 in the hole 44 has been depressed. The rotation may now be continued until the slots in which the coins are positioned come in registration with the lower slots in the shell 16. When this occurs the coins drop from the control mechanism into the coin receptacle. As is discerned this involves a rotation of 180 degrees. In this position the protruding ends of the rods 51 assume their normal position as

shown at 26 in Fig. 4. A rotation in the opposite direction is prevented because the protruding ends of the rods 51 come in contact with the shoulder 27. In order to bring the device to its original position, therefore, it becomes necessary to rotate the handle 40 in the same direction through additional 180 degrees.

By these means all the purposes of the control mechanism have been accomplished by the simple turning of the handle 40 the coin control mechanism has been operated as well as the projection 36 which projection 36 in its rotation has caused to function the merchandise distributing mechanism which is not a part of my device; the control mechanism can only be made to operate by the insertion of the proper coins. If the proper coin is not inserted in the proper slot, it is lost to the operator. No less than the total number of coins intended to operate the device will operate it.

What I claim and mean to secure by Letters Patent is:

25. In a device of the character described, a shell, a coin receptacle, a front plate said shell and coin receptacle secured in operative relationship on said front plate, a cylindrical cup rotatively mounted in said shell, a shaft
30 secured to said cylindrical cup at one end, an end closure secured in the open end of said cylindrical cup, a shaft secured to said end closure, a handle secured to the free end of said first shaft, an arm secured to the free end of said second shaft, means for actuating a commodity delivery device secured to said arm, said shell and cylindrical cup having a plurality of arcuated slots formed therein, coin guides in sliding engagement in said shell, said guides having holes formed therein, a rod in sliding engagement in each of said coin guides said rod projecting in its normal position beyond the periphery of said coin guide, a slide secured to said rod, said coin guides in position in said shell so that said guides will be in registration with certain of the slots in said shell and cylindrical cup and so that the projections of said rods will normally extend through holes in said cylindrical cup into certain other slots in said shell, so that when the proper coin is inserted in any slot, it will depress one of said slides and one of said guides and the projection of one of said rods, and when the proper coins have been inserted in all of the slots of said shell, the slides in all the coin guides and all the rod projections will be depressed so as to permit the rotation of said cylindrical cup in said shell, until the coins come in registration with other slots in said shell and fall into said coin receptacle.

In testimony whereof I affix my signature.
SWAN J. SWANSON.
